(57) **CLAIM**

The ornamental design for a golf club, as shown and described.

DESCRIPTION

FIG. 1 is a bottom, right, and rear isometric view of an ornamental design for a golf club;
FIG. 2 is a top, left, and rear isometric view of the golf club of FIG. 1;
FIG. 3 is a rear elevational view of the golf club of FIG. 1;
FIG. 4 is a front elevational view of the golf club of FIG. 1;
FIG. 5 is a left side elevational view of the golf club of FIG. 1;
FIG. 6 is a right side elevational view of the golf club of FIG. 1;
FIG. 7 is a top plan view of the golf club of FIG. 1; and,
FIG. 8 is a bottom plan view of the golf club of FIG. 1.
The evenly spaced broken lines illustrate portions of the golf club that form no part of the claimed design. The dash-dot-dash broken lines represent boundary lines that form no part of the claimed design.

1 Claim, 7 Drawing Sheets
